LIFT BEDSTEAD

George F. Archer, New York, N. Y.

Application August 12, 1937, Serial No. 158,697

7 Claims. (Cl. 5—10)

In small houses and apartments the space occupied by a bedstead is valuable in day time and the purpose of my invention is to render such space available through the medium of means for lifting the bedstead to the ceiling to thus provide for full occupancy of the floor space when the bedstead is not in use.

The idea of lifting the bedstead to the ceiling is not broadly new with me, but my improvement comprehends the further feature of means for turning the bedstead in its ascent so that the legs will be directed toward the ceiling and the head and footboards will depend, thus providing greater head room, an important factor where the room height is relatively small, and rental space expensive.

To further extend the head room the legs may enter holes provided in the ceiling, enabling the bedstead bottom to lie closely adjacent the ceiling.

The headboard of the bedstead may, for convenience, be positioned near a wall of the room and may include a mirror in its front surface.

The hauling up means may be by cables connected fore and aft, operating over pulleys, the connection with the bedstead being located below the centre of gravity, causing the bedstead to turn in its ascent, guide and brake means being provided.

The lifting may be performed manually or by power means.

Either the mattress and bedding may be secured to the bedstead to retain them when the bedstead is inverted, or said mattress and bedding may be removed.

To give greater clearance the footboard may be hinged and thus capable of folding on to the bed or bedstead to be out of the way.

Also my invention comprehends the provision of means whereby a bedstead in its descent from its upside down position may be caused to turn and right itself so that its legs will alight on the floor and the bedstead will stand on the floor right side up.

Other features and advantages of my invention will hereinafter appear.

In the drawings:

Figure 1 is a perspective view of a bedstead, with bedding, that has been hoisted, and reversed, so that its legs are uppermost and engage the ceiling of a room.

Fig. 2 is an enlarged, side sectional view of the bedstead standing on its legs on the floor of a room and provided with means for hoisting and turning it.

Fig. 3 is an enlarged detail view showing a brake drum mounted on a shaft carried by the bedstead, an extension of said drum that is guided in its vertical movement, and a variably tensioned brake band, connected to the bedstead, to regulate the turning movement thereof.

Fig. 4 is a detail of a modification wherein the foot board is hinged.

Fig. 5 is a view showing a bedstead suspended and counterweighted in the process of turning while being raised to the ceiling.

Fig. 6 is a section on the line 6—6 of Fig. 5.

Fig. 7 is a section on the line 7—7 of Fig. 5, and

Fig. 8 is an end view showing electro-magnetic means for changing the centre of gravity of a bedstead, causing it to rotate in opposite directions.

In said views I have shown the bedstead A provided with side bars 1, headboard 2 and footboard 3, these head and footboards being provided with the legs 4.

Fittings 5 and 6, secured respectively to the head and footboards, in central longitudinal line below the centre of gravity of the bedstead, serve as journal bearings for a shaft 7, so that the bedstead, by means of said fittings, may be rotatable about said shaft.

Shaft 7 has an end 8 projecting beyond fitting 5 and entered within a brake drum 9, and said brake drum is provided with an axial, squared extension 10 that lies between a pair of spaced, vertical guide members 11; and an eye bolt 12, secured to extension 10, is shown to be engaged by one end of a cable 13. The cable is passed over pulleys 14, 15 that are secured to the ceiling 16 of the room containing the bedstead, said cable being here shown as engaged by a windlass 17 or other anchorage secured to the room floor and operable by a motor 18 for raising and lowering the bedstead. Also the cable may be operated manually or by any suitable mechanical means, as is obvious.

As means of cable engagement with the foot portion of the bedstead I provide an eye bolt 19 extended from that end of shaft 7 journalled in fitting 6, and a cable 20 engages a sheave 21 that is secured to the ceiling, so that the bedstead is supported equally fore and aft in its vertical movement and as inverted. Obviously a single cable may be employed to perform the service of cables 13 and 20.

Because the bedstead is pivoted on shaft 7 below its centre of gravity, it will, when being lifted from the floor, turn to direct its legs toward

the ceiling and its upper portion downwardly, and this rotation, if unchecked, would cause the headboard to turn toward the floor before the bedstead had risen sufficiently for the headboard to clear the floor. Therefore I provide means for restraining the turning motion during elevation.

As an example of such restraining means I have shown a brake band composed of the members 22, hinged at their coincident ends 23 to a pintle 24 carried by a lug 25 that is secured to and depends from the headboard 2. The brake band is placed about the drum 9 over intervening brake lining 26, and the free, outturned ends 15 27 of members 22 are connected by a bolt 28 with nut 29; a spring 30, interposed between ends 27 expanding said members 22 against the regulable tension applied by nut 29.

Under the adjusted tension of the brake band 20 the turning movement of the bedstead may be suitably regulated.

The bedding, including the spring mattress, may or may not be removed from the bedstead before hoisting the latter. If left in place then 25 the bedding and mattress may be connected to the bedstead to prevent displacement. To this end I provide removable strips 31 of spring-like material, having bent over ends, said strips being placed across the bedding with their bent over 30 ends caught beneath the side bars of the bedstead.

To increase the head room when the bedstead is raised, inverted, to the ceiling, holes 32 may be formed in the ceiling to receive the legs 4.

35 As illustrated the headboard of the bedstead is located parallel with and adjacent a wall of the room, in this way offering, when elevated, less obstruction to head room, and said headboard is shown as provided with a mirror 33 which is conveniently usable when the headboard is pendent.

In Fig. 4 there appears a modification wherein the footboard is hinged, as at 34, to be thus capable of folding down upon the bedstead to be more out of the way.

45 When the bedstead is being pulled down for use, an operator may easily turn it by hand to bring the legs to rest upon the floor.

In the modification of Figs. 5 to 7 I have shown a bedstead 35 as engaged by a cable 36, passed 50 over pulleys 37, 38 that are secured to the ceiling and provided with a counterweight 39. The same assemblage of cable, pulleys and counterweight is used both for the front and rear of the bedstead.

55 A shaft 40 is extended longitudinally through the bedstead, about in the centre of gravity thereof, and a two-part revolute member, composed of the plates 41 and 42, both engaged with shaft 40, is mounted over an escutcheon 43 that 60 is secured to a panel 44 of the bedstead, roller bearings 45 facilitating the turning movement of said revolute member.

At a point on the plate 41 distant from its shaft 65 engaging centre a stud 46 serves as an anchorage for cable 36, this stud, according to the rotated position of plates 41, 42 determining the centre

of gravity relation of the bedstead. An arm 47 extended from plate 41 permits its manual rotation and a spring detent handle 48 which is engageable in recesses 49 in the escutcheon constitutes means for locking plates 41, 42 in the set 5 position of the revolute member. In the rotated position of members 41, 42 appearing in Fig. 5 the stud 46 is below the centre of gravity and thus in hauling toward the ceiling the bedstead will turn upside down. Then, when about to bring 10 the bedstead down to the floor the plates 41, 42 will be turned by arm 47 to place stud 46 above the centre of gravity, whereupon the bedstead in descent will rotate into its upright position for landing with its legs on the floor.

In the further modification of Fig. 8 I have shown a solenoid 50 whose plunger 51 carries a stub shaft 52 to which a cable 36 is attached, said shaft being shiftable to change the position of the centre of gravity as said solenoid is energized to extend and retract said plunger. Pivotal arms 53, 54, slotted as at 55, to receive shaft 51 serve as lateral guides for said shaft.

Variations within the spirit and scope of my invention are equally comprehended by the foregoing disclosure.

I claim:—

1. The combination with a bedstead of pivotal means therefor located fore and aft below its centre of gravity, fixed pulley means located 30 above the bedstead, and cable means extended over said pulley means and engaging said pivotal means for hauling said bedstead upwardly, and causing the bedstead to turn while ascending.

2. The subject matter of claim 1 including the provision of brake means to retard the turning speed of the bedstead.

3. The subject matter of claim 1 including the provision of vertical guide means and means extended from said bedstead to co-act with said 40 guide means in its vertical movement.

4. The combination with a room having a floor and ceiling of a bedstead having legs that normally rest upon the floor, said ceiling having holes therein adapted to receive said legs, means 45 for hauling said bedstead upwardly, and to cause said bedstead to invert while being raised, and guide means to direct the upward movement of said bedstead causing its legs to register with and enter said holes.

5. The subject matter of claim 4 including the provision of braking means carried by said bedstead to regulate its speed of rotation.

6. The subject matter of claim 1 including the provision of the bedstead footboard being hinged 55 to be foldable.

7. The combination with a bedstead of pivotal means therefor located longitudinally in its centre of gravity, pulley means located above the bedstead cables connected with said pivotal and 60 pulley means, and cable engaging means borne by said pivotal means that are shiftable both below and above said centre of gravity, so that the bedstead may be rotated in either direction while being raised and lowered.

GEORGE F. ARCHER.
